UNITED STATES PATENT OFFICE

2,650,267

HEARING AID CONSTRUCTION

Warren R. Walters, Minneapolis, Minn., assignor
to The Maico Company, Incorporated, Minneapolis, Minn., a corporation of Minnesota

Application August 26, 1949, Serial No. 112,527

3 Claims. (Cl. 179—107)

1

My invention relates generally to electronic hearing aid construction and, more specifically, to means whereby certain of the component parts thereof may be quickly and easily removed and replaced.

My invention contemplates the use of a panel upon which are mounted the tube sockets, condensers, and resistors of the device and certain of the circuit leads thereto. I have found that considerable savings in time and effort can be achieved in the original assembly of the hearing aid when such above-mentioned parts are secured to a removable panel separately of the hearing aid casing. This is particularly true when using a "printed circuit," that is, a circuit in which the leads thereof are imprinted on a non-conducting surface, the printed matter having electrical conducting qualities.

A highly important object of my invention is the provision of novel coupling means for mechanically and electrically joining component elements mounted on a panel with cooperating elements carried by a casing of a hearing aid.

Another object of my invention is the provision of coupling means as above described on a hearing aid casing and a panel unit which will permit rapid removal and replacement of said panel unit without the use of tools or special equipment.

A still further object of my invention is the provision of a coupler for the purpose above-mentioned, which is inexpensive to manufacture and which is efficient and durable in use.

Other highly important objects and advantages of my invention will become apparent from the following detailed specification, appended claims, and attached drawings.

Referring to the drawings, in which like characters indicate like parts throughout the several views:

Fig. 1 is a plan of a hearing aid built in accordance with my invention, the cover plate thereof being removed;

Fig. 2 is a view in plan of the panel unit of my invention on an enlarged scale;

Fig. 3 is a view, partly in side elevation and partly in section, taken substantially on the line 3—3 of Fig. 2 on a still further enlarged scale;

Fig. 4 is an enlarged fragmentary detail, partly in cross-section and partly in side elevation, taken on the line 4—4 of Fig. 1;

Fig. 5 is a view in perspective of one of the coupling elements of my invention; and

Fig. 6 is a wiring diagram of a hearing aid incorporating my novel coupling means.

Referring with greater particularity to the draw-

ings, the numeral 1 indicates an open-topped casing preferably made from synthetic resin or other non-conducting material and adapted to be closed by a cover element not shown. The casing 1, together with the cover element, encloses the microphone, batteries, and audio-amplifier normally used in an electronic hearing aid. The reproducing unit, not shown but of conventional design, is adapted to be connected to a pair of output jacks or connectors 2 and 3 secured to the casing 1. Said reproducing unit may be of the bone conductor type, which is worn against the head above and behind the ear, or of the type which is worn in the ear of the user. The "A" and "B" batteries, indicated by the numerals 4 and 5 respectively, are held in position in the casing 1 by power leads 6 and 7 respectively, and a common lead 8. The leads 6 and 7 are in the nature of spring clips, and the lead 8 is also in the form of a spring clip or bar. A source of "C" current comprising a bias cell 9, in addition to a microphone 10, an "off-on" switch and volume control element 11, and an output transformer 12, are also mounted in the casing 1. With references to Figs. 1 and 6, it will be noted that the transformer 12 is contained within a compartment 13 in the casing 1. A tone control switch 14 is shown in Fig. 1 as having a control arm extending outwardly of the casing 1.

The electronic amplifier tubes customarily used in an electronic hearing aid device, in the present instance three in number, together with the usual condensers and resistors necessary to the operation thereof, are mounted on a removable panel 15. An input tube 16 is removably mounted in a conventional socket 17 rigidly secured to one side of the panel 15. Intermediate amplifier and power output tubes 18 and 19 respectively are removably mounted in respective sockets 20 and 21 also secured to the same side of the panel 15 as is the socket 17. Means for securing the sockets 17, 20, and 21 comprise rigid wire leads extending from the several sockets to the panel 15 and support said sockets in spaced relation to the panel. The current conductor elements or circuit leads between the supporting wires for the several tube sockets and the condensers and resistors of the circuit comprise a "printed circuit," that is, a circuit of leads imprinted upon the panel and utilizing a printing medium containing current-conducting material. It should be noted that the circuit is more or less standard and in itself forms no part of the instant invention.

For the purpose of mounting the panel 15 in the casing 1 and electrically connecting certain

of the circuit leads imprinted on the panel 15 to other circuit leads contained within the casing 1, I provide a plurality of friction-type couplers 22 each comprising a metallic anchoring post 23 and an anchoring clip 24. The posts 23 may be rigidly mounted to the casing in any suitable manner but, preferably and as shown, are screw-threaded thereinto. Each post 23 is diametrically enlarged at its intermediate portion (see Fig. 4) to provide a shoulder 25 which limits movement of the anchoring clips 24 in one direction. Each anchoring clip 24 comprises a generally U-shaped portion 26 and an integrally-formed hook element 27 which is adapted to embrace a post 23 above its shoulder 25. The anchoring clips 24 are secured to the panel 15 preferably by rivets 28 extending through aligned apertures 29 adjacent the free ends of the U-shaped portion 26 and apertures 30 in the panel 15 adjacent the side edges thereof. As shown, the intermediate part of the U-shaped base portion of each clip 24 abuts a side edge of the panel 15, and the hook element 27 extends laterally outwardly of said panel. Clips 24 are made from resilient material such as hard brass, bronze, or the like, and the hooks 27 thereof grip the posts 23 with sufficient tension to insure a good electrical connection therebetween and to prevent accidental removal of the panel 15. As indicated in Figs. 1 and 2, the couplers 22 are so spaced that the panel 15 may be mounted in one way only. In other words, if the panel 15 is turned end for end or upside-down, the clips 24 cannot be aligned with the posts 23 so as to be moved thereonto.

The anchoring clips 24 are connected to various component elements on the panel 15 by means of conduits imprinted on the panel, as indicated in the diagram of Fig. 6. As there shown, the lead 8 is connected to the filaments of the amplifier tubes 16, 18, and 19 through one of the couplers 22 and other leads 31 and 32. Another coupler 22 connects the positive side of the "B" battery 5 with the plates of the input tube 16 and intermediate amplifier tubes 18 through a lead 33 in the casing 1 and a printed lead 34. Leads 35 and 36 in the casing 1 connect the microphone 10 with couplers 22, one connected with a grid in the output tube 16 through a printed lead 37 and the other connected to the printed lead 31 by another printed lead 38. From the above, it should be obvious, without further detailed description of the various leads of the diagram of Fig. 6, that the couplers 22 connect certain elements of the system mounted on the casing 1 with cooperating component elements of the system mounted on the panel 15.

I have found that a hearing aid built in accordance with the invention herein disclosed can be assembled in a relatively short time and with a substantial savings in labor, and that the problem of servicing and repairing this type of hearing aid construction is simplified to an appreciable extent.

While I have disclosed a commercial embodiment of my novel hearing aid construction, it will be understood that the same is capable of modification without departure from the spirit and scope of the invention as defined by the claims.

What I claim is:

1. In a hearing aid of the class described and including a pick-up microphone and an electronic audio amplifier, a casing, means mounting certain component elements of said amplifier on said casing, a mounting panel, means mounting the remaining cooperating components of said amplifier on said mounting panel, connections between cooperating elements on said casing and those mounted on said panel, interposed in each of said connections a friction type coupler, said couplers comprising a plurality of anchoring posts mounted on said casing in spaced parallel relationship, and cooperating anchoring clips secured to said panel adjacent the marginal edge thereof, said clips having laterally-projecting hook-like portions encompassing said anchoring posts and axially slidably thereon, whereby to engage and disengage said clips from their cooperating posts by sliding movements of the panel.

2. The structure defined in claim 1 in which said casing is provided with an opening through which said panel is insertable and removable.

3. A device of the class described, including a pick-up microphone and an electronic amplifier, a casing member, means mounting certain component elements of said amplifier on said casing member, a mounting panel member, means mounting the remaining cooperating components of said amplifier on said mounting panel member, connections between cooperating elements on said casing member and those mounted on said mounting panel member, a friction-type coupler interposed in each of said connections, said couplers each comprising a plurality of anchoring posts mounted on one of said members, and cooperating anchoring clips secured to the other of said members, said clips having laterally-projecting hook-like portions encompassing said anchoring posts and axially slidably thereon whereby to engage and disengage said clips from their cooperating posts by sliding movements of one of said members with respect to the other thereof.

WARREN R. WALTERS.
